FIG. 1 is a perspective view of a pump bulb with three lobes and three multi-concavity faces for an implantable penile prosthetic showing my new design;

FIG. 2 is a front view thereof;

FIG. 3 is a back side view thereof;

FIG. 4 is a left side view thereof; the right side being a mirror image,

FIG. 5 is a top view thereof; and,

FIG. 6 is a bottom view thereof.

In FIGS. 1-5 the broken lines illustrate conduits connected to the pump bulb and form no part of the claimed design.

1 Claim, 4 Drawing Sheets(56)
